UNITED STATES PATENT OFFICE

FRED M. YOUNG, OF RACINE, WISCONSIN

SECTIONAL RADIATOR

Application filed November 28, 1928. Serial No. 321,917.

This invention relates to radiator construction for cooling systems of internal combustion engines and particularly to improvements in the construction of individual radiator core sections. Applicant's co-pending application for patent Serial No. 318,108, filed November 9, 1928, discloses and claims a section of radiator of the general type to which the present improvements relate.

10 The main objects of this invention are to provide an improved structure for avoiding relative vibration of the individual radiator core sections, when the latter are grouped together in an intercommunicative series, to prevent crystallization of the materials thereof and untimely failure of the core sections, to provide an improved construction for strengthening the individual radiator core sections, to provide sectional radiator cores of 20 such construction as to cause substantially uniform compression of all the core sections in mounting the latter in a frame in compact and solid relation, to provide the side structures of each of the individual core sections 25 with registering outwardly protruding bearing portions for resiliently resisting such compression, and to provide outwardly protruding bearing elements having spaced inner and outer continuous edges for resisting 30 distortion thereof. It is also a purpose of the invention to provide improved bearing means for adjacent core sections which permit the passage of air around said bearing means.

35 These objects are attained by means of the structure and arrangement illustrated in the accompanying drawings, which show a radiator core comprising individual core sections or units each having sheet metal side members. Each core section comprises a plurality of water tubes and a plurality of superimposed radiator fins arranged laterally of the water tubes. The front and rear of the radiator core sections are open and the sides 45 thereof are closed by the sheet metal side plates.

The side plates are provided with spaced outwardly extending O-shaped bearing portions arranged in longitudinal alignment substantially throughout the length of the plates.

The central portions of the O-shaped bearing elements are allowed to remain substantially in the plane of the sheet metal plate, thereby providing a protruding ring strengthened by offset inner and outer peripheries. 55

Any suitable number of core sections may be mounted in a rectangular frame with the protruding portions of adjacent side plates in registration with and bearing upon each other. Top and bottom header tanks communicatively connect with the upper and lower ends of the core sections, respectively, and the latter are rigidly secured to the top and bottom of the frame. In order to obtain a compact, solid, vibration resisting unit, the core sections are installed in the frame individually and each section is compressed, by actual pressure, against the adjacent section before its extremities are fixed to the frame. 65

In the accompanying drawings I have 70 illustrated a specific embodiment of my invention, in which:

Figure 1 is a front elevation of an incomplete radiator.

Fig. 2 is a side elevation of a radiator core section. 75

Fig. 3 is a fragmentary section taken on the line 3-3 of Fig. 2.

In the form shown in the drawings, the radiator frame 1 comprises top and bottom header tanks 2 and 3 supported by side members of the frame 1 as shown in Fig. 1 and communicatively connected together by radiator core sections 6, bolted to apertured extensions 4 and 5 of the header tanks 2 and 3 85 respectively.

The core sections 6 each comprise a plurality of water tubes 7, which are firmly held in spaced relation by a plurality of superimposed radiator fins 8. The front and rear of the core sections 6 are open, and the sides of each section are closed by side plates 9. These side plates preferably comprise sheet metal and are provided, substantially throughout their length, with spaced outwardly protruding bosses or bearing surfaces 10. The protruding portions 10 shown in the drawings are substantially O-shaped and are formed by a stamping operation. 95

Any desired configuration may be used but it is 100

preferable to employ a bearing member having an outline of continuous curvature, because the continuous edges thereof suitably resist compression. The central portion 11 of the plate confined within the O-shaped bearing element is substantially in the plane of the sheet metal side plate and the bearing surface 10 is bounded by an outer edge portion or periphery 12 and an inner edge portion or periphery 13.

10 This ring-shaped construction provides two substantially continuous edge portions for firmly supporting the bearing surface 10 in advance of the outer surface 14 of the side plate. The upper and lower extremities of the core section 6 are capped by heads 15 and 16 respectively, each of which are provided with apertured flanges 17.

20 When a sectional radiator embodying my invention is assembled, each section or unit of the radiator core is mounted in the frame 1 individually. The apertures 18 in the extensions 4 and 5 of the top and bottom header tanks 2 and 3 respectively are so arranged as 25 to require the application of pressure on the sections in a lateral direction in order to register the apertures 17' of the flanges 17 therewith.

30 When the first core section is mounted on the frame it is firmly pressed against one side of the frame 1 as viewed in Fig. 1, to that extent required to admit the bolts 19 to be inserted through the apertures 17' and 18 in the flanges and frame respectively. The 35 bearing surfaces 10 which protrude in advance of the side plate 9 are compressed tightly against the side of the frame and are held thereagainst by the bolts 19. The entire space between the vertical sides of the 40 frame 1 is filled by mounting one core section at a time in the frame in the manner described above.

45 After the first core section is properly mounted in the frame, the subsequent sections are compressed one against the other in the order of their installation in the frame, and the bearing surfaces 10 of adjacent core sections are held in registration with each other and firmly held together by attachment 50 of the heads 15 and 16 to the extensions 4 and 5 of the header tanks 2 and 3 respectively.

55 The bearing members formed by the protruding bosses 10 are sufficiently resilient to absorb the usual shock to which a device of the class described is ordinarily subjected, and the edge portions 12 and 13 of the bearing surfaces 10 suitably strengthen the latter for resisting distortion. By means of the above described construction and arrangement 60 the compression between adjacent core sections is uniform throughout the entire radiator, and relative vibration of individual sections or groups of sections is prevented.

65 Although but one specific embodiment of this invention has been herein shown and de-

scribed, it will be understood that details of the construction shown may be altered or omitted without departing from the spirit of this invention as defined by the following claims.

I claim:

1. In a sectional radiator, a frame, core sections mounted in said frame, spacer members separating adjacent sections of said radiator, said spacer members being so formed 75 as to provide horizontal air passages between them.

2. In a sectional radiator, a frame, radiator sections mounted on said frame, a resilient spacer and bearing member separating adjacent sections of said radiator, said spacer member being so formed as to permit the passage horizontally of air between said sections.

Signed at Racine this 21st day of November, 1928.

FRED M. YOUNG.
